United States Patent Office

Des. 185,374
Patented June 2, 1959

185,374

MUZZLE STABILIZER OR SIMILAR ARTICLE FOR FIREARMS

Carl F. Liedke, North Haven, and Gary Wilhelm, New Haven, Conn., assignors to The High Standard Manufacturing Corporation, Hamden, Conn., a corporation of Connecticut

Application January 19, 1959, Serial No. 54,213

Term of patent 14 years

(Cl. D30—1)

Fig. 1

Fig. 2

Fig. 3

Fig. 4

Fig. 1 is a perspective view of a muzzle stabilizer or similar article for firearms showing our new design;

Fig. 2 is a top plan view thereof with only a fragment of the firearm shown for convenience of illustration;

Fig. 3 is a side elevation thereof with only a fragment of the firearm shown for convenience of illustration; and

Fig. 4 is a front end view.

The broken lines shown in the drawings depicting a pistol are for illustrative purposes only.

We claim:

The ornamental design for a muzzle stabilizer or similar article for firearms, substantially as shown and described.
